UNITED STATES PATENT OFFICE.

WILLIAM T. HERNDON, OF LAURINBURG, NORTH CAROLINA, ASSIGNOR OF ONE-HALF
TO GILBERT H. RUSSELL, OF LAURINBURG, NORTH CAROLINA.

STERILIZER.

1,023,646.

Specification of Letters Patent. Patented Apr. 16, 1912.

Application filed July 19, 1910. Serial No. 572,747.

To all whom it may concern:

Be it known that I, WILLIAM T. HERNDON, a citizen of the United States, residing at Laurinburg, in the county of Scotland and 5 State of North Carolina, have invented a new and useful Sterilizer, of which the following is a specification.

This invention relates to improvements in the sterilizing cabinet disclosed in my Patent 10 No. 959,858 dated May 31, 1910; and it is the object of the present invention to simplify the structure thereof, and to provide a more effective closure for the drawers.

Another object of the invention is to provide improved means for automatically returning the drawers to closed position after having been opened.

With these objects in view, the invention consists in a novel construction and arrangement of parts to be hereinafter described 20 and claimed, reference being had to the accompanying drawings, forming a part of this specification, in which—

Figure 1 is a vertical sectional view of 25 the cabinet, one of the drawers being shown in open position. Fig. 2 is a transverse section on the line 2—2 of Fig. 1. Fig. 3 is a plan view showing the drawer closing means in one position. Fig. 4 is a plan view of the 30 drawer closing means in another position.

Referring more specifically to the drawings, 5 denotes a cabinet which may be of any size or style, and which is provided with two drawers 6, but it will be understood that 35 the number of drawers is immaterial, and may be varied as desired. The cabinet also contains a drawer 7, in which the sterilizing substance is placed, and which is mounted at the bottom of the cabinet, so that when the 40 fumes rise, they may pass into the drawers 6, the latter containing the instruments to be sterilized.

In order to prevent the escape of the fumes when the drawers 6 are opened, the 45 following structure is provided:—Each drawer 6 slides between upper and lower horizontal partitions 8 and 9, respectively, the drawer being open on top and also at its rear end. The top partition 8 serves as 50 a closure for the top of the drawer when the latter is in closed position, and also shuts off from the interior of the cabinet that portion of the drawer which remains therein when said drawer is partly opened. To the 55 rear end of the top partition 8 is hinged at

10, a valve for closing the drawer to the interior of the cabinet, when the drawer is opened. The valve comprises a flap 11 having a lateral extension 12 at one end which is hinged to the rear end of the top partition. 60 The other end of the flap is beveled, and fits the beveled rear end 13 of the lower partition 9, when the drawer is opened, as shown in Fig. 1.

The extension 12 carries a staple 14 which 65 is in the path of the laterally extending portion 15^a of a stem 15 which is carried by the drawer, on the inside thereof. The stem may be secured to one of the side walls of the drawer as shown, or to any other convenient part. The stem 15 is so positioned that it engages the staple 14 when the drawer is closed, and thus swings the flap 11 upwardly to open position, thereby permitting the fumes from the sterilizing substance to enter the drawer through its open rear end. When the drawer is pulled open, the stem is withdrawn from the staple, 70 whereupon the flap is released, and drops by gravity, its beveled end seating on the 75 beveled rear end of the lower partition 9, thus closing the space between the upper and lower partitions, and preventing the escape of the fumes from the cabinet. When the flap is in open position, its laterally extending portion 12 is in alinement 80 with the top partition.

The device for automatically closing the drawers comprises a horizontally swinging lever 16 having at one of its ends a curved 90 lateral bend 17, to the extremity of which one end of a coiled spring 18 is connected, the other end of which is made fast to the lower partition 9, or at any other convenient place in the cabinet. The lever is pivoted 95 at 19 to said partition, the pivot being located in the bend 17 of the lever. The straight end of the lever coöperates with pins 20 and 21, respectively, fixed to, and depending from the bottom of the drawer. 100 It will be noted that these two pins are spaced from each other laterally, and one is in advance of the other. On the partition 9 is mounted a guide 22 in which the straight end of the lever works.

The operation of the closing device is as follows: The lever swings forwardly and rearwardly with the drawer. When the drawer is closed, the straight end of the lever extends between the two pins, so that 110

when the drawer is pulled open, the pin 20 engages the lever and swings it on its pivot, whereby the spring 18 is expanded, the latter being free to swing across the pivot 19. 5 In closed position the spring extends on one side of the pivot, so that when the extent of the opening movement of the drawer is such as to keep the spring on this side of the pivot, it will swing the lever in a direction 10 to return the drawer to closed position, when the latter is released. When the drawer is pulled to full open position, the lever 16 swings clear of the pin 20 as shown in Fig. 4, so that the drawer is now released entirely 15 from the lever, and may be pulled wide open, or entirely removed from the cabinet. The forward swing of the lever is limited by the guide 22, the latter being so located as to prevent the lever from swinging out of 20 the path of the pin 21. When the drawer is now returned to closed position, the pin 20 first passes the lever, after which the pin 21 strikes the lever and swings it rearwardly. When the spring 18 swings across the pivot,

it contracts, and swings the lever in a direction to engage the pin 20, thereby pulling the drawer closed, the parts then again assuming the position shown in Fig. 3. 25

What is claimed is:

The combination with a drawer and its 30 housing, of spaced pins carried by the drawer, a J-shaped lever pivoted to the housing to swing in a plane parallel with the drawer bottom, the straight end of the lever extending between the pins and being 35 in engagement therewith when the drawer is closed and out of engagement therewith when the drawer is opened, and a spring fastened at one end to the tail of the lever and its other end to the housing. 40

In testimony that I claim the foregoing as my own, I have hereto affixed my signature in the presence of two witnesses.

WILLIAM T. HERNDON.
